UNITED STATES PATENT OFFICE.

NATHAN H. SUREN, OF NEEDHAM, MASSACHUSETTS, ASSIGNOR TO GAMEWELL FIRE-ALARM TELEGRAPH COMPANY, OF NEW YORK, N. Y., A CORPORATION OF NEW YORK.

FIRE-ALARM BOX.

1,158,742.

Specification of Letters Patent.

Patented Nov. 2, 1915.

Application filed March 7, 1912. Serial No. 682,213.

To all whom it may concern:

Be it known that I, NATHAN H. SUREN, a citizen of the United States, residing at Needham, in the county of Norfolk and State of Massachusetts, have invented an Improvement in Fire-Alarm Boxes, of which the following is a specification.

This invention relates to fire-alarm boxes, and while some of the features are applicable generally to all kinds of fire-alarm boxes, other features are applicable especially to fire-alarm boxes of the non-interference type.

In signal-boxes it is usual to arrange the box-number circuit-controller, or the member employed to operate same, so that it is operated by the signal-wheel, and its movement is very short, and as a result the contacts are separated only a very short distance. While such distance is sufficient under usual conditions, yet in case the circuit is accidentally energized by a heavy current and the circuit-controller is operated during such time, an arc will be formed between the contacts thereof of such proportions as to endanger the apparatus.

One of the objects of this invention is to provide means for operating the box-number circuit-controller by the signal-wheel so as 30 to separate its contacts more widely than usual, the gap or space formed being wide enough to prevent the formation of a destructive arc, even when the circuit is energized by a heavy current. This feature is 35 applicable generally to signal-boxes of all kinds.

In carrying out this feature of my invention one of the contact-members of the box-number circuit-controller is pivotally supported, whereby it is movable toward and from its fellow contact-member, and may be given a wide range of motion, and a controlling-lever for said pivotally supported contact-member is arranged between said 40 member and the signal-wheel, and is adapted to be operated by the signal-wheel, but the leverage is increased to such an extent that the distance between the contacts, when separated, is at least several times the depth of 45 the interdental spaces in the signal-wheel. Furthermore, as the result which it is desired to attain is the reduction of the arc to such an extent that it is not destructive, the contact-members of the circuit-controller are 50 constructed and arranged to produce a mul-

tiple break in the circuit, there being a plurality of contacts provided.

Another object of the invention is to provide said controlling-lever with means whereby it is adapted to coöperate with the 60 armature-lever of a non-interference magnet in such manner that each operates to hold the other under certain conditions, as for instance, the controlling-lever operates to hold the armature-lever in its attracted 65 position while the circuit is open at the home box and the non-interference magnet is de-energized, and to release said armature-lever while the circuit is closed at the home box and the non-interference magnet is ener- 70 gized, yet permitting said armature-lever to be moved into its retracted position in case the non-interference magnet fails to hold it; and the armature-lever operates to hold the controlling-lever free from engagement with 75 the signal-wheel and with the contacts closed when moved into its retracted position by the failure of the non-interference magnet to hold it, incident to the circuit being open at a distant point when it is closed at the 80 home box.

Another object of the invention is to provide means operated by the signaling-train for moving the controlling-lever at the end of a signal, to disengage the signal-wheel 85 and to close the circuit-contacts, and thereafter to hold it in such position while the train is at rest; and said means is adapted to release said controlling-lever to place it in coöperative relation with the signal-wheel at 90 the end of a predetermined period of time after the signaling-train is started, during which period of time the armature-lever is free to be moved into its retracted position in case the non-interference magnet becomes 95 deenergized.

Figure 1 is a front elevation of a non-interference fire-alarm box embodying this invention, the parts being in their normal position. Fig. 2 is a detail showing the 100 parts in the position they will occupy shortly after the box has been pulled, and when transmitting the first signal-impulse. Fig. 3 is a plan view of the parts shown in Fig. 2. Fig. 4 is a detail showing the parts in 105 the position they will occupy when the armature-lever is moved into its retracted position, at the beginning of a signal. Fig. 5 is a detail showing the parts in the position they will occupy when the retracted arma- 110

ture-lever is being returned to its attracted position mechanically by means controlled by the train. Fig. 6 is a modification to be referred to.

Referring to Figs. 1 to 3 illustrating one embodiment of my invention, the signaling-train is of any usual or suitable construction, it having a stop-wheel *a*, provided with a notched flange *a'*; a locking-lever *e* pivoted at *e'*, having a spring-controlled detent *e*² adapted to enter a notch in said flange *a'*, and a pull *e*³ for operating said locking-lever to release the train, and also having a shaft *a*² bearing a signal-wheel *a*³.
 10 *b* represents the stationarily supported resilient contact-member of the box-number circuit-controller, bearing two contacts, and *b'* the movable contact-member, also bearing two contacts, thus to produce a multiple make-and-break in the signal-circuit. The contact-member *b'* is pivoted at *b*², and has connected with it an actuating-spring *b*³, which, when permitted, acts to lift it to disengage the contact-member *b*, and produce
 15 a wide gap or space between the contact. Movements of said contact-member *b'* are controlled by a controlling-lever *c*, which is arranged between said contact-member *b'* and the signal-wheel, and is adapted to be
 20 operated by said signal-wheel. Said controlling-lever *c* is pivoted at *c'*, and has at its upper end a laterally extended pin *c*², with or without a roll thereon, either or both of which may be of insulating material, which
 25 extends over the top of and continuously engages the contact-member *b'* or a cam *b*⁴ thereon according to their relative positions. Said controlling-lever has a laterally extended pin *c*³ near its lower end for engagement with the signal-wheel, in order that the signal-wheel may operate to move said lever on its pivot to permit corresponding movements of the contact-member. Said controlling-lever also has a laterally
 30 extended projection *c*⁴, at a point intermediate its length, which is adapted to enter the path of movement of a pin *c*⁵ on the stop-wheel. The projection *c*⁴ and pin *c*⁵ are so constructed and arranged that when the
 35 projection *c*⁴ is engaged by the pin *c*⁵, as shown in Fig. 1, the controlling-lever will be moved to lift its pin *c*³ free from engagement with the signal-wheel, and to depress its pin *c*², to correspondingly depress the contact-member *b'* to engage the contact-member *b*. And the said pin *c*⁵ is disposed on the stop-wheel so as to engage the projection *c*⁴ after the signal has been transmitted and just as the signaling-train comes
 40 to rest, so that while the train is at rest and the parts are in their normal position, as shown in Fig. 1, the contact-member *b'* is held depressed and the contacts closed, but so far as my invention is concerned, any equivalent part may be arranged on the
 45

train and adapted to move the controlling-lever at the proper time and in the proper manner to accomplish this result. When the train is released and begins to run the pin *c*⁵ slowly moves over the projection *c*⁴, and after a short period of time, as for instance, a period longer than the longest closure in any signal, said pin *c*⁵ completely passes over said projection *c*⁴, and the controlling-lever is then released. During this period of time and while the train is moving to disengage the controlling-lever, the signal-wheel is also moving forward, and at the moment said controlling-lever is released by the pin *c*⁵, the first tooth of the signal-wheel has arrived in a position directly beneath the pin *c*³, so that the controlling-lever is held by said tooth in its normal position. As the train continues to run said first tooth of the signal-wheel passes from under the pin *c*³, whereupon said controlling-lever is free to move, and as it moves its pin *c*³ enters an interdental space in the signal-wheel, and the contact-member *b'* is immediately moved by its actuating-spring *b*³, to disengage the contact-member *b*. As the signal-wheel continues to rotate the controlling-lever is repeatedly oscillated on its pivot by the signal-wheel and the contact-member *b'* is correspondingly moved into and out of engagement with the contact-member *b*, such movement of the controlling-lever corresponding to the teeth of the signal-wheel. The distance said contact-member moves or length of arc through which it moves depends upon the construction or formation of the controlling-lever and the location of the point of engagement of said controlling-lever with the contact-member with respect to the pivot of said member, and the height or shape of the cam *b*⁴. It is herein designed, however, that such movement shall be sufficient to permit the contact-member *b'* to move away from the contact-member *b* a long distance, thereby to form a wide gap or space between the contacts, so as to prevent the formation of a destructive arc in case the circuit is energized by a heavy current when the signal is being sent. In case the signal-wheel is designed to make four rotations, thereby to repeat the signal four times, as is here shown, said controlling-lever will remain in engagement with the signal-wheel until it has completed four rotations, and then the pin *c*⁵ on the stop-wheel will engage the projection *c*⁴, and will positively return the controlling-lever to normal position and depress the contact-member *b'* to close the contacts and hold them closed while the train is at rest. In case the signal-box is of simple type, the operation of the parts will be as above described.

Referring to Fig. 6, wherein a modification of this feature of my invention is

shown, the controlling-lever *c* is arranged entirely beneath the contact-member *b'* and coöperates with the signal-wheel to lift said member. In case the box is of the successive non-interfering type it will be provided with a non-interference magnet *d*, having an armature *d'*, attached to an armature-lever *d''*, pivoted at *d''*, said armature-lever having a pin *d''*, extended laterally from it, which is adapted to engage the end of the locking-lever *e*. Normally the box is shunted or cut out of circuit by any usual or suitable shunt or cut-out switch, not shown, so that its non-interference magnet is normally deenergized, but at such time the pin *d''* on the armature-lever engages the end of the locking-lever *e*, as shown in Fig. 1, so that said armature-lever is mechanically held in its attracted position by said locking-lever. When the box is operated in the usual manner it is cut into circuit and the locking-lever *e* is lifted, and the end portion of said lever rises above the pin *d''*, see Fig. 2, thereby disengaging the armature-lever, and permitting said lever to remain entirely under the influence of the non-interference magnet. In case the circuit is open at a distant point at such moment said armature-lever will be moved immediately by its retractile spring into its retracted position, see Fig. 4, and when so moved its pin *d''* will be moved into a position beneath a tooth *e''* on the end of the locking-lever, but will not engage said lever as said lever is held in elevated position by the flange *a'*. Said armature-lever also has a pin *d''*, extended laterally from it which is adapted to coöperate with an extension *c''* on the controlling-lever *c*, and in case the circuit is open at a distant point when the box is pulled and the armature-lever is consequently moved into its retracted position, as above stated and shown in Fig. 4, said pin *d''* moves beneath said extension *c''*, and acts to hold the controlling-lever in its normal position with the contacts closed until such time as said armature-lever is restored to its normal position. In case the circuit is closed when the box is pulled and remains closed during the time the pin *c''* is passing out of engagement with the projection *c''* on the controlling-lever, then the armature-lever is held in its attracted position during such time by the non-interference magnet, and as soon as said pin *c''* passes out of engagement with said projection *c''*, and the controlling-lever is released, and the first tooth of the signal-wheel passes beneath the pin *c''*, the controlling-lever falls into the first interdental space of the signal-wheel, see Fig. 2, to permit the contact-member *b'* to rise and disengage the contact-member *b* and thereby open the circuit, and the end of the extension *c''* on the controlling-lever is moved to a position opposite the pin *d''*, so as to hold the armature-lever in its attracted position while the circuit is open at the home box. During this regular operation of the box as the controlling-lever is lifted by one of the teeth 70 of the signal-wheel and the contact-member *b'* is correspondingly moved to close the circuits, the extension *c''* is moved to a position above the pin *d''*, thereby releasing the armature-lever, so that while the circuit is 75 closed at the home box said armature-lever is held by the non-interference magnet and is free to respond to a failure of said magnet to hold it, but in case said non-interference magnet should fail to hold it, its 80 pin *d''* will move beneath the extension *c''* on the controlling-lever, and thus hold the controlling-lever in elevated position with the circuit contacts closed. Thus it will be seen that the controlling-lever holds the 85 armature-lever under certain conditions and the armature-lever holds the controlling-lever under certain conditions. In case the armature-lever is retracted after the locking-lever is lifted and the pin *d''* on the 90 armature-lever is moved into the position shown in Fig. 4, it will remain in such position until the stop-wheel *a* moves far enough for the notch in its flange *a'* to come opposite the end of the dog *e''*, see Fig. 5, then 95 the locking-lever *e* is moved downward by its actuating-spring *e''* and the inclined portion *e'''* on the end of said lever is brought into engagement with the pin *d''*, and acts to move said pin *d''* and the armature-lever bearing it until said pin *d''* is 100 brought into engagement with the tooth *e''* on the end of said lever, as shown in Fig. 5. At this moment the end of the flange *a'* adjacent the notch, which is here shown as 105 slightly inclined, engages one side of the end of the dog and acts to lift said dog and the locking-lever bearing it, and said locking-lever then disengages the pin *d''*, but just at this moment said armature-lever 110 is engaged by other means controlled by the train for the purpose of moving said lever into its attracted position mechanically, to again place it under the influence of the non-interference magnet, and said 115 means, as here shown, consists of a pin *f* arranged on one of the train-wheels, as for instance, on a train-wheel secured to the signal-wheel shaft which is adapted to engage the extension *d''* on the lower end of 120 the armature-lever for the purpose of thus mechanically moving said lever into its attracted position. If the circuit is still open when the parts are thus restored then the armature-lever will be retracted again, as 125 shown in Fig. 4; the locking-lever will be held in elevated position by the flange *a'*; and the controlling-lever will be held by the pin *d''*, while the train continues to run for another cycle of its operation. But if the 130

circuit is closed when the parts are thus restored then the armature-lever is held by the non-interference magnet and the signal will be sent.

5 I claim:—

1. In a signal-box, the combination of a box-number circuit-controller comprising a stationary contact-member and a pivoted contact-member, a signal-wheel, and a pivoted controlling-lever having a portion arranged for engagement with the signal-wheel, and a portion arranged for moving engagement with the pivoted contact-member, thus to provide for movement of said pivoted contact-member through a greater arc than the depth of the interdental spaces in the signal-wheel.

2. In a signal-box, the combination of a box-number circuit-controller comprising a stationary contact-member and a pivoted contact-member, an actuating-spring to move said pivoted contact-member in one direction, a cam arranged on said pivoted contact-member, a pivoted controlling-lever having a portion to engage said cam and a portion to engage the signal-wheel, and a signal-wheel to operate said controlling-lever, substantially as described.

3. In a signal-box, the combination of a box-number circuit-controller comprising a stationary contact-member and a pivoted contact-member, the latter bearing a cam, a signal-wheel, and movable means operated by the signal-wheel and engaging said cam to move said contact-member, substantially as described.

4. In a signal-box, the combination of a box-number circuit-controller comprising a stationary contact-member and a pivoted contact-member, the latter bearing a cam, a signal-wheel, and a pivoted controlling-lever engaging the signal-wheel and the cam on said pivoted contact-member, substantially as described.

45 5. In a signal-box, the combination of a box-number circuit-controller comprising a stationary contact-member and a pivoted contact-member, a signal-wheel, and a piv-

oted controlling-lever having a portion arranged for engagement with the signal-wheel, and a portion arranged for moving engagement with the pivoted contact-member, thus to provide for movement of said pivoted contact-member through a greater arc than the depth of the interdental spaces in the signal-wheel, and means operated by the signaling-train to move said controlling-lever out of engagement with the signal-wheel, and to cause said lever to move the pivoted contact-member into engagement with the stationary contact-member at the end of a signal, and to permit the release of said controlling-lever after a prolonged period of time at the beginning of a signal, substantially as described.

6. In a signal-box, the combination of a box-number circuit-controller comprising a stationary contact-member and a pivoted contact-member, an actuating-spring for moving said pivoted contact-member out of engagement with the stationary contact-member, a signal-wheel, a pivoted controlling-lever arranged for cooperation with said pivoted contact-member and signal-wheel to provide for a movement of said contact-member through a wide range of motion, thereby to widely separate the contacts, and means operated by the signaling-train to move said controlling-lever out of engagement with the signal-wheel and to cause said lever to move the pivoted contact-member against the force of its actuating-spring into engagement with the stationary contact-member at the end of a signal, permitting the release of said controlling-lever after a prolonged period of time at the beginning of a signal, substantially as described.

In testimony whereof, I have signed my name to this specification, in the presence of two subscribing witnesses.

NATHAN H. SUREN.
